UNITED STATES PATENT OFFICE.

ROCKWELL L. GALLUP, OF CHICAGO, ILLINOIS, ASSIGNOR, BY MESNE ASSIGNMENTS, TO BARRY-WEHMILLER MACHINERY COMPANY, OF ST. LOUIS, MISSOURI, A CORPORATION OF MISSOURI.

BOTTLE-WASHING MACHINE.

1,161,469.

Specification of Letters Patent. Patented Nov. 23, 1915.

Application filed February 17, 1912. Serial No. 678,816.

To all whom it may concern:

Be it known that I, ROCKWELL L. GALLUP, a citizen of the United States, residing at Chicago, in the county of Cook and State of Illinois, have invented certain new and useful Improvements in Bottle-Washing Machines, of which the following is a specification.

This invention pertains to bottle washing machines of the general character disclosed in my co-pending application Serial No. 647,005, filed August 31, 1911, and aims to provide certain improvements and novel features of construction adapted to improve the efficiency and operation of such a machine.

One of the objects of the present invention is the provision of novel means for separating the labels, removed from the bottles, from the washing water and delivering the separated labels outside the machine.

Another object is to produce a machine in which the shotting spindles and the water supplying chamber therefor can be bodily removed from the machine for purposes of inspection and repair.

Still another object is the provision of an improved construction whereby the shot delivered by the shotting spindles is returned to the shotting cups and any scattered shot is collected in receptacles from which it may be removed for subsequent use.

Other objects and many of the advantages of the invention will be apparent to those skilled in the art as the invention is better understood from the following description when considered in connection with the accompanying drawings.

Referring to the drawings, Figure 1 is a side elevation of a bottle washing machine embodying my invention, a portion of the side wall of the machine being broken away to more clearly illustrate the interior mechanism; Fig. 2 is a transverse sectional view taken substantially on the line 2—2 of Fig. 1; Fig. 3 is a fragmentary end elevation looking toward the right in Fig. 2; Fig. 4 is a transverse sectional view taken substantially on the line 4—4 of Fig. 1; Fig. 5 is a detail view of the screen and the water chamber; Fig. 6 is a longitudinal sectional view taken on the line 6—6 of Fig. 5; Fig. 7 is an enlarged detail view of one of the

cup-shaped sockets forming the plate above the shotting spindles. Fig. 8 is a vertical sectional view showing a spindle in washing position within a bottle.

From the drawings it will be observed that this machine comprises an inclosed frame 11 within which the bottle washing operations take place, an endless carrier 12 encircling sprocket wheels 13 and 14 at the ends of the machine being adapted to carry the bottles through the machine from one end to the other. Reciprocating rods 15 operated by eccentrics 16 are equipped with dogs 17 which engage with the carrier and feed the same forward by an intermittent movement. The washing spindles 19 are adapted to be raised and lowered by hydraulic cylinders 21 or other suitable mechanism to introduce the spindles into the bottles disposed on the carrier between the intermittent movements thereof. The mechanism thus far described may be of usual or preferred construction and the details thereof are fully illustrated and described in my co-pending application to which reference has hereinbefore been made.

The water used for washing purposes in the spindles 19 is supplied to said spindles by a pump in the usual manner and in order that this water may be used repeatedly it is necessary to separate the labels therefrom since these labels if drawn into the pump will eventually clog it up and prevent its operation. Instead of permitting the water which has been sprayed over the inside and outside of the bottles to flow directly back into the tank or containing chamber 22, I have, in this instance, provided a plate 23 beneath the carrier 12, said plate being inclined from one end to the other so that the labels and other solid material carried thereby will flow into the transversely extending conduit or pipe 24. The plate 23 must, of course, be perforated to permit the introduction of the spindles 19 therethrough, but to limit the quantity of water which will flow through these perforations to a minimum I have provided bearings or sockets 25 (Figs. 1 and 7) through which the spindles 19 pass, said bearings being but slightly larger than the spindles so that a relatively tight fit is effected. These bearings also serve to steady the spindles and prevent vibration as they are raised and lowered. Since water issues

constantly from the ends of the spindles it will be obvious that no opportunity is afforded for labels or other solid material to pass through the plate even when the 5 spindles are in the lowered position shown in Fig. 1.

The conduit 24 extends transversely of the machine and communicates at one end with a tubular member 26 mounted outside 10 the machine in a casing 27. The inclined partition 28 divides the tubular member into two sections. A cylindrical screen consisting of circular end members 29 and an encircling screen 31 is mounted to revolve 15 about the tubular member and the peripheries of the circular members 29 are provided with gear teeth adapted to mesh and be driven by the pinions 32 fixed on a constantly rotating shaft 33 extending trans- 20 versely of the machine and adapted to be driven through a gear 34 or any other preferred driving mechanism. The tubular member 26 is provided with a port or opening below the partition 28 so that the wash- 25 ing water will flow from the conduit 24 through this port and through the screen from whence it will be conducted back into the reservoir or tank 22 by the surrounding casing 27. It will be obvious that by this 30 construction water is permitted to pass through the screen which will separate therefrom labels and other solid matter which will be collected upon the interior of the screen. As the screen is constantly re- 35 volving this material will be carried by the screen to a position above the partition 28. At this point and adjacent the screen I have provided a pipe 35 connected with any suitable source of water or other fluid supply 40 under pressure, this pipe being provided on its under side with perforations through which jets of water are discharged against the screen 31. The labels and other solid matter clinging to the interior of the screen 45 will be removed therefrom by the issuing jets of water and will fall upon the partition 28 from whence they will be conducted to any suitable discharge receptacle by a delivery pipe 36.

50 The greater part of the labels and other solid material removed from the bottles will be separated from the washing water by the mechanism just described, but for the purpose of further insuring the pump 55 against the entrance of labels and other undesirable solid matter thereinto I have provided a further screening mechanism illustrated in detail in Figs. 5 and 6. This mechanism, as will be observed, comprises 60 a flat circular perforated plate 37 mounted on the inner end of a shaft 38 which is continuously revolved by a driven gear 39 from any suitable driving mechanism. A ring or annular shoulder 41 serves as a guide for 65 the screen 37 and also forms a compartment

inside the side wall 42 of the machine. The screen 37 is disposed across the end of the suction pipe 43 to the pump so that all water entering this pipe must pass through the screen. Any pieces of label and solid material not previously collected by the screens 31 will be deposited upon the inner 70 face of the screen 37. Since this screen is constantly revolved the solid material and labels will be carried around with the screen 75 but when they reach an upper position opposite the open side of a conduit 44 they are blown off from the screen by jets of water or other fluid issuing from a perforated pipe 45 connected with any suitable 80 source of water supply under pressure. The labels are conducted by the conduit 44 to any suitable discharge point outside the machine. It will be manifest from the foregoing that I have provided two screening 85 mechanisms for removing the labels and other solid matter from the washing water so that this water may be used repeatedly for washing the bottles.

After the bottles have been washed by the washing spindles 19 they are subjected to the action of a series of shotting spindles 46 as in my previous machine, the shotting spindles being carried upon a water chamber 47 connected by a hose 48 with any suitable source of water supply under pressure. Since it is desirable to frequently gain access to the shotting spindles for the purpose of inspecting the same, supplying them with shot and occasionally making repairs, I have so mounted the chamber 47 that it may be bodily slid out of the machine. To this end the frame 48 carried upon hydraulic cylinders 49 is equipped with a series of rollers 51 upon which the chamber 47 is supported. The side of the machine is provided with an opening 52 normally closed by a door and through which the water chamber and the shotting spindles may be removed. A frame or supporting table 53 provided with rollers 54 may be attached to the side of the machine in alignment with the opening thereby enabling the water chamber 47 and the shotting spindles to be slid out of the opening 52 into the dotted line position shown in Fig. 4 where the necessary inspection and repairs may be made. A detachable coupling 55 connects the hose 48 with the water chamber and this may be disconnected 103 when the chamber is to be removed.

The shot cups 56 within which the lower ends of the shotting spindles 46 are mounted are adapted to contain a quantity of shot which is delivered to the bottles on the carrier by the water discharged through the spindles. In order that the shot may be delivered back to the cups 56 I have provided a plate 57 situated above the shotting spindles and formed with cup-shaped sockets 115 120 125 130

58 through which the spindles 46 pass, these sockets being adapted to convey the shot back to the cups 56. In case a bottle should be broken or missing from the carrier the 5 shot discharged by its particular spindle will be delivered to the top of the machine where a deflector 59 is situated to prevent undue scattering of the shot. For the purpose of collecting and saving such shot as 10 is not returned to the shot cups by the sockets 58 I have provided at each end of the plate 57 receptacles 61 and 62 into which the scattered shot will be conducted by the inclined portions of the plate on either side 15 of the sockets 58. The shot collected in these receptacles may be removed when desired and returned to the cups.

It is believed that my invention and its mode of operation will be understood from 20 the foregoing without further description and it will be obvious that various deviations in mechanical structure from the construction shown and described may be resorted to without exceeding the scope of the 25 following claims.

I claim:

1. In a bottle washing machine, the combination of a water reservoir, means for conveying bottles through the machine, 30 means including a plurality of spindles for applying water to the bottles to remove the labels therefrom, means located outside the water reservoir for separating the labels from the water, means, including a plate 35 perforated for the passage of said spindles therethrough and a conduit positioned at one edge of said plate, for conducting water and the labels carried thereby to said separating means, and means for returning the 40 water to said reservoir.

2. In a bottle washing machine, the combination of a bottle carrier, a bottle washer comprising a plurality of reciprocatory spindles, a conduit, an inclined plate disposed 45 beneath said carrier and adapted to conduct the foul washing water and labels to said conduit, said plate having perforations for

the passage of the spindles therethrough, and means positioned at one end of the conduit for removing the labels from said washing water. 50

3. In a bottle washing machine, the combination of a bottle carrier, a bottle washer, an inclined plate arranged beneath said carrier, conduits disposed at the ends of said 55 plate, pipes connecting said conduits, and label separating means connected with the lower conduit.

4. In a bottle washing machine, the combination of a bottle support, a plurality of 60 washing spindles, an inclined plate disposed above said spindles, and bearing members carried by said plate to receive said washing spindles.

5. In a bottle washing machine, the combination of a plurality of reciprocatory shooting spindles, a perforated plate thereabove provided with a plurality of cup-shaped sockets to receive said spindles, and a receptacle at the end of the plate into 70 which scattered shot is collected. 65

6. In a bottle washing machine, the combination of a plurality of reciprocatory shooting spindles, and a plate disposed thereabove, said plate being provided with cup-shaped sockets adapted to return the shot 75 into operative position relatively to the spindles.

7. In a bottle washing machine, the combination of an inclosed frame, a bottle carrier mounted to travel through said frame, a track mounted in the frame beneath said carrier, a water chamber slidably supported on the track, a series of washing spindles mounted on the chamber, and a removable 80 door in the side of said frame in alignment with the ends of the track through which the water chamber may be removed from the machine. 85
